UNITED STATES PATENT OFFICE.

FRITZ DEIMEL, OF BERLIN, GERMANY; JOSEPH SIMSON, ATTORNEY IN FACT, ASSIGNEE
TO SAID JOSEPH SIMSON INDIVIDUALLY.

FRictional POCKET-IGNITER.

1,018,100.

Specification of Letters Patent. Patented Feb. 20, 1912.

Application filed September 1, 1910. Serial No. 580,087.

To all whom it may concern:

Be it known that I, FRITZ DEIMEL, a subject of the German Emperor, and residing at Berlin, Germany, have invented certain new and useful Improvements in Frictional Pocket-Igniters, of which the following is a specification.

My invention relates to igniters and a primary object is to provide an improved pocket igniter in which sparks are produced by friction and ignite a combustible on a wick.

My igniter comprises a pyrophorous body, *i. e.*, a so-called sparker, and a scraper arranged movable relatively to one another outside a receptacle which contains the combustible and is normally closed by a hinged cover, and the apparatus for producing sparks is constructed in a very advantageous manner inasmuch as a part of the same, *e. g.* the scraper, is attached to one end of a spring which automatically returns the scraper into its normal position, the other end of the spring being attached securely to the receptacle.

One illustrative embodiment of my invention is represented by way of example in the accompanying drawing, where:

Figure 1 shows my igniter in elevation and Fig. 2 is a top plan view of the same.

Referring to the drawing, the guide *h* for the wick having a hinged cover *i* and a tongue or lug *k* is provided on the receptacle *a* for the combustible. The holder *f* carries the sparker *e* and is a tube traversing the receptacle *a*, but may be located outside the same if preferred; the sparker *e* is pressed upwardly by the spring *g* against the scraper *d*; the latter passes through the lug *l* attached to the receptacle and through the bent spring *b* screwed to the bottom of the receptacle, and is secured in position by the nut *c*, as clearly shown.

When the igniter is to be used the hinged cap *i* is raised by pushing the lug *k* upward and the spring *b* carrying the scraper *d*

pressed inwardly toward the cap, whereby the same scrapes the pyrophorous body *e* and throws or directly conducts the sparks in the direction of the wick and thereby ignites the combustible thereon.

The pyrophorous body may be of any suitable composition, *e. g.* 70% cerium and 30% iron.

This igniter has the advantage that the cap can be opened and the sparker operated with only one hand, and that, in addition, the full pressure of the hand is utilized for the requisite movement of the scraper, whereby considerable showers of sparks are produced.

I claim:

1. An igniter of the character described, comprising in combination, a substantially rectangular receptacle having a tubular guide for a wick, a hinged cap normally closing the end of the guide, a spring-pressed sparker mounted on the receptacle adjacent the guide, a spring, having one end secured to the receptacle, substantially parallel with the sides of the receptacle, and a substantially horizontal scraper carried by the other end of the spring and adapted to scrape the sparker, substantially as shown.

2. An igniter of the character described, comprising in combination, a substantially rectangular receptacle having a wick-tube, an upwardly spring-pressed sparker mounted on the receptacle adjacent the tube, a spring, having one end secured to the receptacle, substantially parallel with the sides of the receptacle, and a substantially horizontal scraper carried by the other end of the spring and adapted to scrape the sparker, substantially as shown.

In testimony whereof, I affix my signature in the presence of two witnesses.

FRITZ DEIMEL.
